CLAIM

The ornamental design for a device for fitting over a thumb to discourage thumb-sucking, as shown in the accompanying drawings and described above.

DESCRIPTION

FIG. 1 is a bottom front right perspective view of a first embodiment of a device for fitting over a thumb to discourage thumb-sucking, showing my new design;

FIG. 2 is a rear elevation view of the device of FIG. 1;

FIG. 3 is a front elevation view of the device of FIG. 1;

FIG. 4 is a rear elevation view of the device of FIG. 1;

FIG. 5 is a right elevation view of the device of FIG. 1;

FIG. 6 is a left elevation view of the device of FIG. 1;

FIG. 7 is a top plan view of the device of FIG. 1;

FIG. 8 is a bottom plan view of the device of FIG. 1;

FIG. 9 is a top front right perspective view of a second embodiment of a device for fitting over a thumb to discourage thumb-sucking, showing my new design in a condition of use;

FIG. 10 is a rear perspective view of the device of FIG. 9;

FIG. 11 is a front elevation view of the device of FIG. 9;

FIG. 12 is a rear elevation view of the device of FIG. 9;

FIG. 13 is a right elevation view of the device of FIG. 9;

FIG. 14 is a left elevation view of the device of FIG. 9;

FIG. 15 is a top plan view of the device of FIG. 9; and,

FIG. 16 is a bottom plan view of the device of FIG. 9.

In FIGS. 1 through 16, the broken lines illustrate portions of the device for fitting over a thumb to discourage thumb-sucking that form no part of the claim. In FIGS. 9 through 16, the broken line showing of a hand depicts unclaimed environmental subject matter.
